UNITED STATES PATENT OFFICE.

FOREST V. DETWILER, OF CHICAGO, ILLINOIS.

HEAT-RETAINING COOKER.

1,260,257.

Specification of Letters Patent. Patented Mar. 19, 1918.

Application filed February 20, 1913. Serial No. 749,653.

To all whom it may concern:

Be it known that I, FOREST V. DETWILER, a citizen of the United States, residing at Chicago, in the county of Cook and State of Illinois, have invented certain new and useful Improvements in Heat-Retaining Cookers, of which the following is a specification.

This invention relates to improvements in heat retaining, or fireless cookers as they are sometimes called, and one of the objects of the invention is to provide an improved apparatus of this class which will be of a sanitary construction and from which the cooking chamber or receptacle may be readily removed and as readily replaced without dismantling the parts.

To the attainment of these ends and the accomplishment of other new and useful objects as will appear the invention consists in the features of novelty in the construction, combination and arrangement of the several parts hereinafter more fully described and claimed and shown in the accompanying drawings illustrating the invention and in which;

Figure 1 is a perspective view of an improved apparatus of this class constructed in accordance with the principles of this invention and with parts broken away.

Fig. 2 is a vertical sectional view of one of the compartments showing the cooking chamber or receptacle in section.

Fig. 3 is a central vertical sectional view of the parts shown in Fig. 1.

Fig. 4 is a vertical transverse sectional view taken on line 4-4 Fig. 1 showing the doors closed and with parts removed and parts broken away.

Fig. 5 is a transverse sectional view of the vessel holding rack for one of the compartments.

Fig. 6 is a sectional detail view of a portion of the rack.

Fig. 7 is a perspective view of the removable tray or pan provided for the purpose of catching any water of condensation which forms inside of the apparatus.

Referring more particularly to the drawings and in the present exemplification of this invention the numeral 10 designates generally an inclosing casing which may be of any desired size and configuration but is preferably rectangular in cross-section and is supported by suitable legs or supports 11.

This casing is divided into two compartments, one of which compartments opens

through the front of the casing, and a closure 12 which swings about upright pivots is provided for the opening. The other compartment opens through the top of the 60 casing, and the closure 13 which preferably swings about horizontal pivots is provided for the latter.

Arranged within the compartment which opens through the front of the casing is insulating material 14 which is provided with dead air spaces 15 and the insulating material is arranged to form a central compartment 16 of a size substantially equal to the size of the opening through the front of the 70 casing and with which opening the compartment registers. This compartment is provided with a lining 17 preferably of metal which forms a top, bottom, rear and side walls, and the forward extremities of the 75 top, bottom and side walls are shaped to form inwardly projecting portions 18 arranged adjacent the opening in the compartment.

A frame 19 also constructed of sheet material is arranged within the opening in the front of the compartment and is adapted to fill the space between the edge of the lining 18 and the front wall of the casing and also operates to form a jam or abutment for the 85 closure 12.

Arranged within the compartment thus formed is a food receptacle or chamber 20 preferably constructed of sheet material and provided with an open side. This receptacle 90 or chamber 20 is adapted to be inserted and withdrawn from the compartment and when inserted the portions of the receptacle adjacent the open side will engage and rest against the adjacent faces of the inwardly 95 projecting portions 18, which latter serve to support the front end of the receptacle and to hold it spaced from the walls of the compartment. The open end of the receptacle may be provided with deflected portions 21 100 which abut the shoulder formed on the outer side of the offset portions 18.

If desired additional supports 22 may be provided for the receptacle 20 and these supports 22 are arranged in the space 105 formed between the rear wall of the casing and the rear face of the offset portion 18 on the bottom of the compartment, and are preferably of a height slightly less than the height of the offset portion. These supports 110 22 preferably extend to the rear wall of the compartment and are provided with open-

ings 23 so that they will not interfere with the circulation of the heated air.

Additional spacing members 24 may be provided between the upright walls of the 5 receptacle and the compartment, and these spacing members 24 are also provided with openings 25 so as not to interfere with the circulation of the heated air.

A closure 26 is pivotally mounted as at 10 27 to swing about a horizontal pivot, to close the open side of the receptacle. The closure 26 is preferably insulated and is located between the closure 12 and the outer edge of the receptacle 20. A suitable fastening device 28 may be provided for locking the closure 26 when closed.

The receptacle 20 may be provided with handles 29 by means of which it may be readily withdrawn or inserted into the 20 compartment and the receptacle is also provided with brackets 30 on the interior thereof which brackets serve as supports for the heating elements 31 or a rack 32 upon which latter a vessel containing the 25 articles to be cooked may be placed.

In order to permit the heated air to pass out of the receptacle 20 and into the space between the wall of the apparatus and the wall of the receptacle, the latter is provided 30 with openings 33. This is particularly advantageous when the heating elements 31 are employed for baking purposes, as the steam will be forced or driven out of these openings by the heat from the plates. With 35 out the openings 33, baking or roasting can not be performed, as the articles will not brown on account of the steam or moisture.

A tray or pan 33^a is removably arranged within the casing and in such a position that 40 the compartment 20 will rest thereon and is of such a size that the wall 33^b thereof will be adjacent the side and rear walls of the compartment. This tray is provided for the purpose of catching and confining any water 45 of condensation that may form on the side of the removable receptacle and in the space between the receptacle and the compartment wall. The tray preferably rests upon the supports 22 and is of a thickness so that 50 the front edge of the tray will not project above the supporting surface of the portion 18 of the lining 17. If desired the tray may be slightly depressed at its center.

Leading from the compartment to the outside of the casing 10 is a tube or passage 34 which has communication with a condenser 35 located on the outside of the casing, so that any moisture in the heated air, will pass in to the condenser through a tubular 55 member 34 to be condensed. This condenser 35 is provided with a removable section 36 adapted to be emptied of any water of condensation, and is also provided with an open upper extremity adapted to be closed 60 by a closure 37. When this closure 37 is

opened the vapor will pass out of the open end of the condenser but when it is closed the vapor will be confined therein and condensed.

Arranged within the other compartment 70 of the casing is insulating material 38 similar to the insulating material 14, and is provided with dead air spaces 39. The insulating material is arranged so as to form a central compartment which registers with 75 the opening through the top of the casing, and this compartment is provided with a lining 40 preferably constructed of metal. The top of the insulation, that is the portion adjacent the opening, is cut away to 80 form an enlarged opening, and the top of the casing surrounding this opening is recessed as shown in Figs. 1 and 3. A sheet metal covering 41 is arranged over the recessed portion in the top of the casing so 85 that its edges 42 will overhang the edges of the adjacent walls of the recessed portion and this sheet material 41 extends into the enlarged portion of the chamber as at 43 to form a covering for the adjacent portion of 90 the insulation. This covering projects over the upper edges of the lining and is offset or deflected to form an inwardly projecting annular shoulder 44.

Arranged within the compartment thus 95 formed is a removable receptacle 45 the upper edge of which is shaped to form a circumferential outwardly projecting flange 46 adapted to rest upon the support or shouldered portion 44. This receptacle 45 100 is of such a size that when placed within the compartment formed by the lining 40, it will be supported by the flange 46 above the bottom of the compartment while it will also be spaced from the wall of the compartment to form an air space therebetween, and around the receptacle. The receptacle 45 is also of a size slightly smaller than the opening formed by the shoulder 44, so that while being placed into the compartment, it will, as it is forced into the compartment, force almost all of the air out of the compartment through the top thereof, the receptacle 45 together with the flange 46 and the shoulder 44 coöoperating 110 with the walls of the compartment to form a closed annular space around the receptacle, to prevent the transmission of heat. Furthermore, the shoulder 44 is preferably cupped or shaped as shown to conform with 120 the contour of the flange 46, so that when the flange is seated therein, water of condensation accumulating at this point will form a water seal for the annular space. The closure 13 is provided with an insulated projecting portion 47 adapted to enter the open end of the compartment and to project a short distance into the receptacle 45 to form a closure for the latter.

The portion 47 is provided with recesses 125

or grooves 47^a of any desired depth, opening through the periphery of said portion in such a manner that they will be deeper at their extremities adjacent the lower end of 5 the portion and gradually decrease in depth as they extend toward the cover 13, until their ends merge into the periphery of the said portion, and are provided for the purpose of allowing any vapor or steam to 10 escape into the space around the portion 47 of the closure, and from the space, into the tubular passage 55 leading to the condenser 56.

Arranged within the removable receptacle 15 45 is a rack comprising spaced uprights 48 the upper and lower extremities of which are connected by cross portions 49 secured thereto in any desired or suitable manner and constructed of any suitable material.

20 Reticulated material 50 such as wire gauze, grating or the like is secured to the rack so as to extend substantially half way around the rack, thereby leaving one side of the rack open (see particularly Fig. 5). 25 Spaced supports 51 are secured to the uprights 48 to project inwardly therefrom and these supports are preferably in the form of brackets for removably holding the vessel supporting racks 52 in position.

30 Any number of heating elements 53 may be arranged upon the supports 49—52 and the supports 52 are removable for the purpose of accommodating the rack to vessels of different heights.

35 In use the proper supports are placed in the rack from the open side and the vessels then placed upon the supports, the heating elements 53 being also arranged in position either upon the rack or directly upon the 40 vessel, or the vessel may be placed upon one of the heating elements. After the parts are thus assembled the rack may be transported by the handle 54 and placed into the receptacle 45, after which the closure 13 is 45 closed and the heat radiated by the heating elements will cause the cooking operation to proceed.

In order to permit the escape of moisture from the receptacle 45 a tubular member 55 50 is provided which has communication with the interior of the compartment and passes through the wall of the casing and is connected with a condenser 56 similar in all respects to the condenser 35 on the other 55 side of the apparatus. When the closure 13 is closed it enters the recessed portion in the top of the casing so that its upper face will stand flush or substantially flush with the face of the remaining portion of the top of 60 the inclosing casing.

With this improved construction it will be manifest that there is provided a casing having a deep well or receptacle in one end, while in the other end of the casing is arranged an oven having an opening through

the side of the casing. Furthermore, the cooking receptacles are not only so arranged as to form a space between the outer walls of the receptacle and the adjacent walls of the compartment within which they are 70 located, but these receptacles may be readily removed when desired and as readily replaced and when so replaced and the respective closures closed, the heated air will be confined therein.

75 Arranged beneath the closure 12 and in close proximity thereto is a trough 57 which may be of any desired size and configuration, and is provided for the purpose of catching and accumulating any water of 80 condensation which may form on the exterior surface of the closure 12. This trough 57 is removably supported in any desired or suitable manner preferably by means of bayonet slots 58 in one of the walls of the 85 trough, which slots coöperate with pins or lugs 59 on the casing.

While in the present exemplification of this invention the preferred forms of construction are herein shown and described it 90 is to be understood that various changes may be made in the details of construction and in the arrangement of the several parts, without departing from the spirit of this invention.

95 What is claimed as new is:—

1. In an apparatus of the class described, the combination of a casing having a heat insulated chamber therein provided with an opening through one wall of the casing, a 100 closure for such opening, and an open receptacle independent of and arranged on the outside of the casing, said receptacle being detachably connected with the casing beneath the said closure for independent removal therefrom and adapted to receive the water of condensation.

2. In an apparatus of the class described, the combination of a casing having an entrance opening, a food receptacle therein, a 110 closure for the casing, said closure having a portion projecting therefrom and forming a closure for the receptacle, and a vapor outlet formed in the said projecting portion and leading from the receptacle.

3. In an apparatus of the class described, the combination of an inclosing casing having an entrance opening, a food receptacle therein and insulated from the wall thereof, a closure for the opening in the casing, said 120 closure having a portion forming a closure for the receptacle, and one or more channels formed in the periphery of said portion and forming an outlet for vapor from the receptacle.

4. In an apparatus of the class described, the combination of an inclosing casing having an entrance opening, a food receptacle therein and insulated from the wall thereof, a closure for the opening in the casing, said 130

closure having a portion forming a closure for the receptacle, one or more channels formed in the periphery of said portion and forming an outlet for vapor from the receptacle, the said portion of the closure being shaped to form a space between the periphery thereof and the casing, and with which space the said channels communicate, and an outlet leading from the space to the outside of the casing.

5. An apparatus of the class described embodying in combination an inclosing casing having an entrance opening provided with a support within and projecting from 10 the wall of the casing, said support being arranged adjacent the opening, and a removable receptacle adapted to be placed therein, said receptacle having means adapted to engage and rest upon the said support 15 for suspending the receptacle within the casing out of contact with the walls thereof to form a space between the casing wall and the receptacle, and whereby water of condensation will be trapped from entering the 20 said space.

6. An apparatus of the class described embodying in combination an inclosing casing having an entrance opening provided with a support disposed within the casing 25 and projecting from the wall thereof adjacent the opening, and a removable receptacle adapted to be placed therein, said receptacle having an outwardly projecting flange adjacent its opening adapted to engage and rest upon the support for suspending the receptacle and holding it out of contact with the walls of the casing, and whereby water of condensation will be trapped from entering the said space.

40 7. An apparatus of the class described including in combination an inclosing casing having an entrance opening, a receptacle adapted to be inserted into and removed from the casing through the opening, said 45 receptacle being of a size somewhat less than the casing, means disposed within and supported by the casing wall to project across the space between the receptacle and casing walls and a supporting lip on the receptacle 50 adapted to engage and rest upon the said

means for supporting the receptacle out of contact with the walls of the casing and whereby water of condensation will be trapped from entering the said space, said lip being spaced some distance from the entrance to the said opening.

55 8. An apparatus of the class described including in combination an inclosing casing, a receptacle adapted to be inserted into and removed from the casing, said receptacle being of a size somewhat less than the casing, means disposed within and supported by the casing wall to project across the space between the receptacle and casing walls, and a supporting lip on the receptacle adapted 60 to engage and rest upon the said supporting means for suspending the receptacle out of contact with the walls of the casing, and whereby water of condensation will be trapped from entering said space, the said 65 receptacle operating when inserted into the casing to force a greater portion of the air from the casing.

70 9. An apparatus of the class described embodying an outer and an inner receptacle, the latter being of a size somewhat less than the former to form a space therebetween, means co-operating with the inner receptacle and entirely within the outer receptacle and forming a substantial closure for such space, 75 whereby water of condensation will be trapped from entering the said space, the air being forced from the space by the insertion of the removable receptacle, said closure embodying a flange formed on the 80 inner receptacle adjacent its entrance opening and a support connected with the outer receptacle, said flange adapted to engage and rest upon the said support for suspending the inner receptacle and for holding it 85 out of contact with the walls of the outer receptacle.

90 In testimony whereof I have signed my name to this specification, in the presence of two subscribing witnesses, on this 17th day of February A. D. 1913.
